RESPIRATOR BAG AND ASSEMBLY

Harry F. Shindel, Reading, Pa., assignor to
Willson Products, Inc., Reading, Pa., a corpora-
tion of Pennsylvania

Application October 22, 1932, Serial No. 639,026

4 Claims. (Cl. 128—146)

This invention relates to respirators and particularly to an improved respirator bag of novel construction and also to improvements in the general construction and assembly of such respirators.

In many instances the filter bags of respirators are of cumbersome construction and partially obstruct the vision of a wearer above and at the sides of the bag. An object of the present invention is to provide a respirator bag of simple construction adapted to be associated with the other parts of a respirator in such manner as not to obstruct the vision of a wearer. Another object is to provide a respirator in which a maximum amount of its surface is effective to filter air breathed by a wearer. A further object is to improve the respirator construction so as to eliminate undesired ingress and egress of air at certain points thereof.

Other objects and advantages of the invention will be apparent upon consideration of the following detailed description of an illustrative embodiment of the invention when read in conjunction with the appended claims and the accompanying drawing in which:

Figure 1 is a plan view of a respirator embodying the invention with some parts broken away and others shown in section to illustrate details of construction;

Figure 2 is a side view of the filter bag and associated parts of the respirator; and

Figure 3 is a perspective view of an expander for the respirator bag.

In the drawing, the numeral 10 designates a mask of suitable material and construction adapted to be applied over the nose and mouth of a wearer so that the air breathed by the wearer is drawn in through a respirator bag 11 and exhaled through the mask outlet 12. Mask 10 extends at one end through a suitable opening in an end wall of a mask ring or casing 13 which may comprise a pair of interengaged screw caps 14 and 15.

The mask 10 is provided with a suitable flange 16 overlying and held in engagement with the interior surface of the end wall of cap 14 by a peripheral flange 17 on a valve plate or disc 18 formed with apertures 20 for the passage of air from bag 11 and provided with a one way flap valve 21. A peripheral flange 22 extending from the opposite side of disc 18 binds a flange 23 on the outlet 24 of bag 11 against the interior surface of the end wall of cap 15 which is formed with an opening through which the bag outlet extends into the casing so that the flange 23 over-

lies the said wall. With the above described arrangement the flanges 17 and 22 on disc 18 by binding the flanges 16, 23 of the mask and bag, respectively, against the end walls of casing 13 enclose and seal the passage interiorly of casing 13 through which air is drawn to the mask from the respirator bag.

According to the present invention the respirator bag 11 comprises a pair of similar discs 25 of suitable material, for example a fabric such as wool felt, laid together and joined as by stitching, cementing, or the like, along the major part of their circumferential edges. Each disc is provided with a preferably integral extension 26 the upper edge 27 of which is tangential to the periphery of the respective disc at its top and hence parallel to the center line thereof. The widths of the extended portions 26 are preferably such that their lower edges 28 are disposed above the center lines of the respective discs and may also be parallel to the edges 27 thereof so that when the extended portions of the discs are secured together along their side edges 27 and 28 a substantially cylindrical outlet is provided for the bag 11. The attaching flange 23 may be integral with the outlet 24 or may comprise an annulus of suitable material attached at its inner peripheral edge to the outlet, for example by providing it with an upstanding flange suitably secured to the wall of the outlet as indicated in Fig. 1.

It may be noted that the outlet 24 is disposed above the center of the bag with its upper side tangential to the upper part of bag 11 and when attached to ring 13 causes the bag to extend forwardly and downwardly so that the upper part of the bag does not obstruct the wearer's vision. The outer-end wall portions of outlet 24 which merge into the substantially circular sides of the bag are convergent and thus cause the latter to be disposed centrally of the ring 13. As the bag is a relatively thin disk-like cylinder disposed vertically edgewise centrally of ring 13 the wearer's vision is not obstructed by the sides of the bag, and in fact all of the latter is practically invisible to a wearer.

In order that the respirator bag of the invention may perform its functions properly a novel expander 30 is provided for preventing collapsing of the sides of the bag due to the breathing action or otherwise. The expander 30 comprises a preferably continuous wire loop bent into an arcuate form and having its branches extending adjacent each other.

As shown in Figs. 1 and 3, in which the ex-

ponents *a* and *b* designate the respective branches, the loop 30 is reversely bent at a plurality of points so that portions 31 of each branch of the loop are offset alternately at opposite sides of the center line of the loop and are disposed substantially parallel to similarly offset portions of the other branch; and the respective offset portions are connected to contiguous loop portions by inclined portions 32 thereof which being oppositely inclined in the respective branches intersect each other, substantially on the center line of the loop. When the loop is inserted within the respirator bag 11 as indicated in Figs. 1 and 2 the offset portions 31 contact the sides of the bag and maintain the latter distended so that a maximum amount of its surface is effective to filter air. Inasmuch as the outlet 24 is of greater width than the relatively thin substantially flat sided bag the parallel end portions 33 of the loop are more widely spaced than the side contacting portions 31.

Although an illustrative embodiment of the invention has been described in detail there are many changes and variations which may be made without departing from the principles of the invention and it is intended to include all such changes and variations within the scope of the appended claims.

What I claim is:

- 30 1. A respirator comprising a face mask having an air inlet with a surrounding attaching flange, a relatively flat adjustably secured respirator bag having an air outlet with a surrounding attaching flange, a pair of connecting clamping caps adapted to receive the respective attaching flanges and peripherally engage them within their annular cap rims, and a flange clamping spacer enclosed by said caps and comprising a disc portion having reversely extending peripheral flanges engaging opposed peripheral faces of said attaching flanges, said disc having a valve closed aperture controlling the admission of air from said respirator bag to said mask inlet.
- 40 2. A respirator comprising a face mask having

an air inlet with a surrounding attaching flange, a respirator bag having an air outlet with a surrounding attaching flange, a pair of complementary clamping caps having apertured ends and surrounding rim portions adapted to receive the respective attaching flanges and peripherally engage them within their cap rims, and a flange engaging spacer ring clampingly seating said attaching flanges to their respective clamping cap rims to form an air-tight chamber connecting 10 said face mask inlet and said respirator bag outlet. 5

3. A respirator comprising a face mask having an air inlet with a surrounding attaching flange, a respirator bag having an air outlet aperture 15 and a separate flat ring annularly secured to said wall adjacent said aperture to form a surrounding attaching flange, a pair of complementary clamping caps having apertured ends and surrounding rim portions adapted to receive the 20 respective attaching flanges and peripherally engage them within their cap rims, and a flange engaging spacer ring clampingly seating said attaching flanges to their respective clamping cap rims to form an air-tight chamber connecting 25 said face mask inlet and said respirator bag outlet. 25

4. In combination with a respirator mask having a spacing ring forming an air communicating passageway extension from said mask, means for connecting said ring to said mask so as to form an air tight junction therewith, and an end-apertured cap having a flange adapted to clampingly engage against the projecting end of said ring, of an air filter bag having an air outlet 35 and an apertured flat attaching flange surrounding said outlet and fixedly secured to the surrounding peripheral edge of the latter, said attaching flange being adapted to be entered through said cap end aperture and clampingly 40 engaged between said ring end and said cap flange. 30
